CLAIM

The ornamental design for dual accessory rail mount for vertical foregrips, as shown and described.

DESCRIPTION

FIG. 1 is an upper front left perspective of an accessory rail mount design for a foregrip.

FIG. 2 is an upper front right perspective view of the design of FIG. 1.

FIG. 3 is an upper rear right perspective view of the design of FIG. 1.

FIG. 4 is an upper rear left perspective view of the design of FIG. 1.

FIG. 5 is a lower front left perspective view of the design of FIG. 1.

FIG. 6 is a lower front right perspective view of the design of FIG. 1.

FIG. 7 is a front view of the design of FIG. 1.

FIG. 8 is a rear view of the design of FIG. 1.

FIG. 9 is a top view of the design of FIG. 1.

FIG. 10 is a bottom view of the design of FIG. 1.

FIG. 11 is a left side view of the design of FIG. 1; and,

FIG. 12 is a right side view of the design of FIG. 1.

The broken lines in FIGS. 1–12 are for illustrative purposes and form no part of the claimed design.
